UNITED STATES PATENT OFFICE.

LUTHER M. PHILLIPS, OF ALTOONA, PENNSYLVANIA, ASSIGNOR OF ONE-HALF TO W. F. SELLERS, OF ALTOONA, PENNSYLVANIA.

EYEGLASSES.

SPECIFICATION forming part of Letters Patent No. 692,069, dated January 28, 1902.

Application filed March 12, 1901. Serial No. 50,813. (No model.)

To all whom it may concern:

Be it known that I, LUTHER M. PHILLIPS, a citizen of the United States, residing at Altoona, in the county of Blair and State of Pennsylvania, have invented certain new and useful Improvements in Eyeglasses; and I do hereby declare the following to be a full, clear, and exact description of the invention, such as will enable others skilled in the art to which it appertains to make and use the same.

My invention relates to improvements in eyeglasses; and the object is to provide a nose-guard for eyeglasses which is of improved and simplified construction, which is certain in action, effective and pleasant in application, and durable in use.

The invention therefore consists in the novel construction and aggroupment of elements, as will be hereinafter specified and particularly pointed out and distinctly claimed.

I have fully and clearly illustrated the invention in the accompanying drawings, wherein—

Figure 1 is a view in front elevation of eyeglasses to which the invention is shown as applied. Fig. 2 is a view in section on the line 2 2 of Fig. 1. Fig. 3 is a detail view of one of the nose-guards removed from its connection to the frame. Fig. 4 is a detail enlarged transverse section showing the sectional contour of the spiral springs.

Referring to the drawings, A A designate the eyeglass-frames, connected in resilient relation by means of a nose-spring 1, the ends of which are clamped and secured in suitable posts 2 2, extending from the inner portions of the frames and formed with vertically-disposed flanged brackets 3 3, in which the ends of the nose-spring are clamped by screws 4, projected through the ends of the nose-spring into the screw-threaded sockets formed in the said posts. These elements may be of any of the approved patterns or styles suited to the purposes.

B B designate the nose-guards, consisting of elongated segments of spiral-spring wires

of proper lengths, preferably flattened on one side, as at 5, forming a contacting or bearing surface. The nose-guards are held in operative relation to the frames by means of inwardly-directed and downwardly-extending fastening-pieces 6 6, having their upper ends held between the flanges of the brackets 3 by the screws 4, and their lower ends suitably secured to the spiral nose-guards at about the middle thereof, leaving the upper and lower portions above and below the point of connection free in their resilient action against the inclines of the nose. The connection is so made that the spirals stand inwardly inclined from bottom to top, and also inclined from bottom to top to the vertical plane of the frame or glasses, so that the grasp fits the nose and at the same time holds the glasses in the true visual plane in their relation to the eyes of the wearer.

A nose-guard of the construction above mentioned and as illustrated in the drawings will be found especially comfortable to the wearer, and their continuous use will not wear recesses or corns on the inclines of the nose, yet the grasp has sufficient tension to retain the glasses. This may be attributed to the ventilation afforded through the center of the spirals and its distribution through the interstices of the walls.

What I claim is—

The combination with the eyeglass-frame; the nose-spring and the posts holding the nose-spring, of brackets secured to the posts, and flexible nose-guards composed of segments of spiral springs having free ends and secured to the brackets intermediate their ends and having flattened surfaces to engage the inclines of the nose.

In testimony whereof I affix my signature in presence of two witnesses.

LUTHER M. PHILLIPS.
